AUTOMATIC RAILWAY SWITCHING
SYSTEM

Matthew H. Loughridge, Bogota, N. J.

Application February 24, 1932, Serial No. 594,771

12 Claims. (Cl. 246—31)

This invention relates to railroads and relates particularly to an automatic system for operating the track switches on a railroad. It has for an object to divert traffic from one track to another 5 when the first track is filled and to again divert the traffic to the first track when the second track is filled. Another object of the invention is to release traffic from a side track to a main track in a predetermined order. Another object 10 of the invention is to provide a system of electric control for power operated track switches associated with the block system; a further object is to control the operation of trackway switches by the cooperation of trains or cars spaced on the 15 trackway at certain points. The invention embodies means for controlling the train or cars by controlling the power system of the train and also controlling the braking system. The system controls trains moving from left to right and operates 20 the facing switches after the traffic has passed over the switch and accumulated on the track, and it operates the trailing switches, where the traffic leaves the sidings before the trains pass over the switches. When the switch is 25 operated for traffic from the side track it is maintained in this position by the continuous movement of the traffic until the side track is cleared.

The invention will be more particularly understood from the following specification and the accompanying drawings, which illustrate the invention in diagram form and in which,

Fig. 1 is a diagram of a main track and two connecting tracks for receiving traffic from the main track;

Fig. 2 is a diagram of one form of car wiring that may be used on the motive units with this invention;

Fig. 3 is a diagram showing a pair of side tracks feeding a main track with means for automatically operating the switches on the track.

In the operation of a railroad there are portions of track over which it is not possible to maintain uniform speed and the slowing up of traffic occasioned by this condition can be prevented by the addition of one or more supplementary tracks over which the slow speed traffic may be operated. There are also conditions arising in the operation of a railroad in which it is necessary to inspect the rolling stock at some intermediate point on its journey. This requires that the traffic be stopped until the inspection can be made, after which the journey may be resumed.

In order to cause as little delay as possible to traffic under these and similar conditions, the supplementary tracks with the automatic switching arrangement shown in Figs. 1 and 3 may be used. In Fig. 1, the traffic is operated at normal speed on the main track until the section where the switches are located is reached. On this

section means are provided for reducing the operating speed so that the turnout switches may be safely negotiated. The arrangement is such that when traffic on main track A is diverted over switch D to the side track B the traffic continues over this route until the track B is filled. The traffic then continues over track C, being diverted at switch E on account of tracks A and B being filled with traffic, and when track C is ultimately filled with traffic, switch E is automatically set for the main track and traffic is again diverted to either track A or track B. It should be stated that the track switches are assumed for descriptive purposes to be in the normal position when they are set for the straight 15 or main track A and are assumed to be reversed when set for the side tracks. The acute angle of the triangle shown at the switch points, according to standard practice, indicates the closed position of the switch point, that is, when it is closed 20 against the adjoining rail. As shown in Fig. 1, the traffic is directed over track A, with the tracks free from traffic until switches D or E are reversed by means not shown.

The diagram in Fig. 3 is a continuation of the diagram in Fig. 1 and shows a system for automatically operating switches to enable the traffic from the side tracks B and C to be diverted to the main track A. In this arrangement, when switch F is reversed which occurs when there is not traffic on the main track approaching the switch, traffic will continue to flow from track B to track A until there is an interruption in this traffic. The system is so arranged that an interruption in the continuous flow of traffic from track B and traffic approaching the switch on track A, will restore switch F to the normal position and clear the way for traffic from tracks A and C. Traffic from track C over switch G reversed flows into track A until there is an interruption in the flow which causes the switch G to be moved to the normal position and provides for traffic movements on the straight track A.

In the drawings, 11 and 12 represent the running rails of the track, 13 is the power wire which may be in the form of a trolley wire or third rail, and 13a is a section of the power wire located at the switch turnouts and arranged for lower speeds than where the power wire 13 is used. The power wire 13 is energized from supply mains at 17, one of which mains connects by the wire 19 to 13 and the other wire connects to the trackway 12 this applies to the power mains 13 throughout the system. The power wire 13a is energized from the supply mains 17 through the resistance 18 which causes the lower speed of operation.

The trackway is provided with a block wire 14 on one side of the trackway and another block wire 15 on the opposite side of the trackway. The block wire 14 is energized from the power wire 13

through the resistance 16. The operation of the power wire and the block system will be understood from the car wiring diagram in Fig. 2 in which 21 represents the running wheels on the rails, 22 is the trolley connecting with the power wire 13 and controlled by the armature 27 of the train control relay 26, which, when energized, connects the power wire to wire 28 leading to motor armature 29 and the field coil 30 and from there to the ground connection 31 on the axle 25 of the running wheels. The wire leading to contact 24 is grounded at 25 and connects with block wire 14 while wire 23 leading to relay 26 connects with block wire 15.

15 When the block wire 15 is energized it is apparent that relay 26 will be energized and the train will proceed. On the other hand when block wire 15 is deenergized relay 26 is deenergized and the train stops. It will be observed that at the end 20 of each block the wire 14 of the block ahead connects with the wire 15 of the block in the rear so that if a car should be in the block ahead, with the contact 24 grounding the wire 14, it is apparent that the rear wire 15 would thereby be substantially deenergized and in consequence a train in the rear block would be stopped until the block ahead is cleared.

The block system referred to is more fully described in U. S. Patent 1,617,402 issued February 15, 1927, and the vehicle wiring in Fig. 2 is more particularly described in U. S. Patent 1,805,551 issued May 19, 1931. It should be noted that the diagram in Fig. 2 includes the differential braking system of the latter patent and is indicated 35 by the eccentric 32, the connection 33 and the shoe 34 as equivalent to the braking system referred to. As to the automatic operation of the track switches, this application is a continuation in part of my co-pending application, Serial No. 40 168,189 filed February 14, 1927, now Patent 1,857,760, May 10, 1932.

The operation of switch D will now be described. The switch is provided with an operating motor 64 which has a field indicated by N which, when energized, moves the switch to the normal position and it has a second field indicated by R which, when energized, moves the switch to the reverse position. A switch circuit controller is operatively connected with the switch points for cutting off the power to the motor when the switch operation has been completed.

On track B when section 36 is occupied the corresponding block wire is grounded and in consequence block relay 35 connected thereto is deenergized. Also, when block section 38 is occupied the corresponding wire is substantially deenergized and block relay 37 is deenergized. When relays 35 and 37 are both deenergized a circuit is established from the battery wire indicated by B through back contact 56 of relay 35, wire 55, back contact 54 of relay 37, wire 53, and stick relay 51 to ground return at 52. This energizes the stick relay 51 and establishes the stick circuit from the battery B through contact 59 established by the switch points in the reverse position through wire 58 and through contact 57 to relay 51 and to ground at 52. This holds the relay 51 energized until the circuit is interrupted at 59 by changing the position of the switch points. When relay 51 is energized a circuit is established from the energy wire B through contact 60, controlled by the switch point, wire 61, contact 62 of relay 51, wire 63, normal field N, motor armature 64, wire 65, contact 66 of block relay 39 in the energized position and wire 70a to the return circuit.

The relay 39 is connected to the block wire 40 and prevents the switch motor being operated when the track section in which the switch is located is occupied by a train.

The circuit just described energizes the motor 64 and the normal field N thereby causing the switch D to be operated from the reverse to the normal position diverting traffic from track B to track A. This system is intended for traffic operated on the closest possible headway but it is desirable to prevent the reverse operation of switch D until the track B has been completely filled with traffic. Track B is provided with a block system whereby trains diverted to this track continue to move along the track until the traffic is actually stopped. This occurs when each block is occupied by a train, including the blocks 36 and 38. In order, however, to be able to fill track B with trains without operating the switch D by the trains on this track following each other as closely as the block system will permit the block 36 is so arranged that a train takes less time in passing over this block than in passing over block 38 so that under normal conditions the relays 35 and 37 are not both deenergized at the same time until traffic is actually stopped. For this purpose block 36 is shorter than block 38, also block 36 is in the section supplied by the high speed trolley wire 13 while block 38 is supplied by the low speed trolley wire 13a. For instance, when a train enters block 36, it releases block 40 for operation at normal speed by removing the ground on wire 38, but before a train on block 40 reaches block 38 to deenergize relay 37, the preceding train has cleared block 36 and relay 35 has time to become energized to interrupt the circuit of relay 51 at 56. When a train occupies the block immediately in advance of block 36, as occurs when this track is filled with trains up to block 36, the next train is stopped in block 36 and the train following that is stopped in block 38. Thus track B is filled with trains, spaced by the block system on this track, relays 35 and 37 are deenergized at the same time and conditions are established for reversing switch D. Thus a selective system is provided which enables traffic to feed into a side track until this track is filled to capacity.

The switch E is provided with a mechanism corresponding to the switch D and with similar controlling circuits similarly referenced with a prime mark on the reference characters. The relay 41 connects to the block wire 42 to prevent the operation of the switch E when the train is passing over the switch. The stick relay 51' is controlled by traffic on track B and on the right hand end of track A through wire 53', back contact 75 of block relay 37a, wire 76 and back contact 77 of block relay 35a, wire 78, back contact 54, of relay 37, wire 55 and back contact 56 of relay 35 to the energy wire B. By this arrangement relay 51' is energized when tracks A and B are filled as indicated by the deenergization of block relays 35, 37, 35a and 37a at the same time. When relay 51' is energized the circuit of motor 64' and reverse field R is established, thus reversing switch E and diverting traffic from track A to track C.

Track C is provided with a section 48 which has insulated joints on the track rails at 45, a track battery 49 and a track relay 47. Also a section 44 similarly insulated is provided having the track battery 46 and a track relay 43. This construction corresponds with the ordinary track circuit which may be used alternatively to the block system shown for operating the block re-

lays connected to the block wires, such as 35, 37, etc.

When the sections 44 and 48 are occupied at the same time a circuit is established from the energy wire B through back contact 82 of relay 43, wire 84, back contact 80, of relay 47, wire 79, switch contact 72' in the reverse position, wire 74', contact 70' of relay 51', deenergized normal field N and motor 64'. This establishes the condition for changing the switch E from the reverse to the normal position. It will be noted that during the time the traffic is being diverted to track C either or both of tracks A and B under normal conditions will have been cleared of traffic by trains moving out of these tracks at the opposite end, the forward movement of the trains releasing the block sections 36 and 38 on track B and the block sections controlling relays 35a and 37a on track A so that some of the relays 35, 37, 35a, 20 and 37a will be energized and in consequence relay 51' will be deenergized to establish the circuit associated with the motor 64'. Should the tracks B and A not have cleared when track C is filled with traffic, then it is apparent that relay 25 51' will remain energized and the capacity of the system has been reached and further traffic approaching on track A would be halted by the block system until some one of the tracks cleared. That is, if track A or B clears, then switch E would be moved to divert traffic from track C, but if track C clears first, the traffic would continue over this track. It should be noted that the track section controlling relay 35a, and the track section controlling the relay 43 are shorter than the preceding track sections and are arranged for higher speed traffic similar to the arrangement at section 36 on track B. Switch D is changed from the normal position to the reversed position by a circuit established when switch E is reversed from energy wire B, through switch contact 74 closed when E is reversed, wire 73, switch contact 72 of switch D in the normal position, wire 71, contact 70 of relay 51 in the deenergized position, reverse field coil R to motor 64 and the return circuit. 40 Thus if track B is clear so that relay 51 is deenergized, switch D will be reversed during the time traffic is directed to track C, but if track B is occupied, switch D remains normal and after E is changed to normal, traffic continues on track A. In ordinary operation it will be noted that traffic runs over track B, then over track A, then over track C and then back to track B, repeating this cycle.

The arrangement in Fig. 3 shows the opposite ends of the side tracks B and C connecting to the main track A and, as arranged, may divert traffic from these side tracks to the main track in the same order in which it was diverted from the main track to the side tracks in Fig. 1. In this arrangement the block wires at switch F are controlled by a circuit controller 101 connected with the switch points and so arranged that when the switch is normal the block wire 103 is fed through wire 102, switch 101 and resistance 16 from the energized power wire 13, while the block wire 105 being disconnected at 101, is deenergized; and when the switch is reversed the block wire 105 is fed through wire 104, circuit controller 101 in the reverse position indicated by the dotted line and resistance 16 to power wire 13, while the block wire 103 is disconnected at 101 and is deenergized. The relay 108 is connected with the resistance 16 by wire 109 and is grounded on the rail by wire 110 so that this relay becomes deenergized with the train either on section 103 or 105, according

to the position of switch F. Relay 108 through contact 153 and wire 152 controls the circuit of the switch motor 135 to prevent the operation of the motor when a train is passing over the switch. A similar construction is provided at switch G with circuits similarly referenced but distinguished by a prime mark.

Track section 114 controls block relay 113 and track section 112 controls block relay 111. Track section 116 controls block relay 115, track section 118 controls block relay 117 and track section 120 controls block relay 119; also, track section 122 controls block relay 121, and track section 124 controls block relay 123.

Relays 111, 113, 121 and 123 controlling the holding circuit of the stick relays 126, 126' may be of the slow pick up type to hold the circuit closed during any interruption that may occur as the train moves from one block to the next.

The results to be secured will be understood by considering that when switch F is reversed traffic will continue to flow from track B to A but upon an interruption of this traffic switch F is changed to normal and traffic continues on track A, but upon interruption of this traffic, switch G is reversed and traffic continues from track C to track A, until there is an interruption in this traffic at which time switch G is changed to normal provided there is traffic on track A. Traffic on the main track maintains the switches normal but upon an interruption of this traffic the switches are automatically reversed for traffic from the side tracks. The control in Fig. 3 is shown applied to the trailing switches F and G, but the same system of control can be used to operate facing switches.

When sections 112 and 114 on track B are occupied and sections 103, 116 and 106 on track A are clear, switch F is reversed, or is maintained reversed by the following control. Stick relay 126 is energized from the battery wire B through contact 139 of block relay 115 energized, wire 129, contact 128 of block relay 108' energized wire 127, relay 126 and return wire 110. When relay 126 is energized the stick circuit is established through contact 141a, wire 131, contact 132 of relay 111 deenergized, wire 133 and contact 134 of relay 113 deenergized to battery wire B. Thus when the sections 106 and 116 on track A are clear, relay 126 is energized and this relay is maintained energized as long as sections 112 and 114 on track B are occupied. Section 112 is preferably longer than section 114 and may be arranged for a lower speed than section 114 so that trains moving in a continuous stream from track B over switch F will cause relays 111 and 113 to be deenergized at the same time but when this stream is interrupted both of these relays will not be deenergized at the same time and in consequence the holding circuit of relay 126 will be interrupted. It should be noted that the sections of block wires 112 and 114 may be replaced by the ordinary track circuit and the vehicle circuits may correspond to U. S. Patent 1,857,760, May 10, 1932.

When stick relay 126 is deenergized a circuit is established for moving switch F from the reverse to the normal position starting at the battery wire B through contact 139, controlled by switch F, wire 138, contact 137 of relay 126 deenergized, wire 136, normal field coil N, motor 135, wire 152, contact 153 of relay 108 and return by wire 110 and ground on the track rails. When stick relay 126 is energized a circuit is established to change the switch F from the normal to the reverse position, starting at the battery wire B, through con-

tact 143 on switch F, wire 142, contact 141 of relay 126 energized, wire 140, reverse field R and motor 135 to wire 152 as before. By this arrangement it will be noted that when traffic is established from track B to track A it continues over this route until there is an interruption which de-energizes relay 126. This interruption also requires the presence of trains in block 106 or 116 on track A, when switch F is changed from the reverse to the normal position and traffic continues on track A.

Switch G is controlled in a manner similar to switch F with corresponding reference characters designating the circuits and indicated by a prime mark. The stick relay 126' is controlled through contact 144 of relay 117 in the energized position, wire 145, contact 146 of relay 119 in the energized position to the energy wire B, and the stick circuit is controlled through wire 147, contact 148 of relay 121 deenergized, wire 149, contact 150 of relay 123 deenergized to battery wire B. When track A is clear relay 126' is energized, reversing switch G for traffic from track C and it remains in this position as long as traffic on track C maintains relays 121 and 123 deenergized.

The block relays are the relays that respond to the presence of a train in the block. Usually a train in the block deenergizes the block relay. When the usual track circuits are used as at 43 and 47, the block relays are known as track relays.

It will be noted that in operation when track A is clear relay 126 is energized and traffic is established from track B to track A and when track B has been exhausted of traffic and there is traffic on track A relay 126 is deenergized and switch F is changed to the normal position so that traffic may continue from track A or track C. When traffic on track A has been exhausted switch G is reversed for traffic from track C by energizing relay 126' and traffic then continues from track C until an interruption occurs, that is, until the continuous flow of traffic from this track ceases thereby deenergizing relay 126'. If at this time traffic has accumulated on track A, switch G is changed to the normal position by deenergizing relay 126' to permit the flow of traffic on track A. When the traffic on track A is interrupted immediately in rear of switch F then this switch is reversed by energizing relay 126 for traffic from track B. It should be observed that track relay 108 for the block section where the switch is located is deenergized as soon as a train enters section 105 or 103. This relay controls the circuit of the switch motor 135 at 153 so that the switch cannot operate when this relay is deenergized. Thus, if either of relays 111 or 113 should temporarily become energized the switch cannot thereby change its position.

The normal operation assumes that trains can follow each other as closely as the block spacing will permit on each track and when the switch is set for this traffic it remains set until the block spacing is changed.

The automatic operation of the switches described can be applied in a variety of ways in addition to the particular arrangement shown in the diagrams and the invention is not to be understood as limited to this specific arrangement shown.

The system as described is assumed to operate traffic alternately over tracks B, A and C, which traffic is fed from the left side of track A, Fig. 1, and is taken off on the right side of track A, Fig. 3. The feed and take off portions of track are designed for high speed, or continuous traffic,

while the multiple track portion is designed for low speed or for traffic that may be stopped.

When switch D is reversed to direct traffic to track B, it remains in this position until blocks 36 and 38 are occupied at the same time, that is 5 until track B is filled. When switch E is reversed to direct traffic to track C it remains in this position until blocks 44 and 48 are occupied at the same time, that is until the track is filled. Thus if traffic over B or over C is not sufficient to 10 fill these tracks it continues over the route established until the track is filled and this removes the traffic from the other tracks.

When switch F is reversed it remains reversed as long as an uninterrupted stream of traffic flows 15 from track B to track A. Should a train arrive at block 116 on track A at the time switch F is reversed, it will be stopped on account of the block wire being deenergized by switch controller 101. Thus traffic may accumulate on track A 20 while track B is clearing, but after B clears, switch F is automatically changed to normal for traffic from track A provided there is traffic on track A. Track B can thus be used for through traffic while the other two tracks remain idle.

In the same way, when switch G is reversed it remains reversed as long as there is an uninterrupted stream of traffic from track C to track A, and if a train reached block 118 on track A it will be stopped by the block system which deenergizes 30 the block wire by switch controller 101' until switch G is placed normal. This occurs when the traffic has cleared from track C and when there is a train on blocks 118 or 120 of track A. It should be noted that as traffic is established 35 on track B or on track C, track A is exhausted of traffic and no further traffic can enter this track until switches D and E are placed normal. The established route over track B or track C continues until these tracks are filled which 40 changes the position of the switches for traffic on track A.

In practice, traffic fills track B and is stopped for loading, inspection or other purposes on this track, then switch D is moved to the normal position and track A is filled with traffic that may be stopped on this track for any purpose, then switch E is reversed and traffic is directed to track C.

If traffic clears track B during the time switch E is reversed, switch D is reversed to direct traffic 50 again over track B when switch E becomes normal. In this way as track B is again filled, track A is cleared and then the traffic that has been stopped on track C is cleared while track A fills with traffic and with tracks B and A filled, switch 55 E is again reversed to fill track C. If switch E should become normal before track B clears switch D would not reverse and traffic would continue on track A, but if track A is also filled at this time, switch E cannot be moved to normal. 60

If the system should so operate that track B clears before track A fills then switch E would not be reversed because as shown the circuit of relay 51' requires relays 35 and 37 on track B and relays 35a and 37a on track A to be deenergized 65 to complete its pick-up circuit. In this case traffic would continue on track A until either switch D or switch E were reversed by means not shown on the drawings.

It should be noted that when only two tracks 70 are involved with one connecting switch, the system is much simplified as for instance, tracks A and C and switch E. In this case the control of relay 51' is limited to relays 37a and 35a with wire 18 connected to energy B, so that when relays 75

35a and 37a are both deenergized, switch E is reversed and when either or both of these relays are energized, switch E is moved to normal, provided sections 44 and 48 of track C are occupied.

5 Thus, filling track A alone reverses switch E and filling track C with track A cleared places switch E normal without control from track B. The facing switch E in this case is operated by a pair of adjacent blocks on the two tracks only which 10 are connected by the switch, corresponding to the control of the trailing switches F and G.

Having thus described my invention, I claim:

1. An automatic switching system for railway tracks, comprising a main track and a side track, 15 a block system for spacing trains on said tracks, a switch connecting said tracks and means on the trackway responsive to trains on certain adjoining blocks on said side track at the same time for changing the position of said switch to divert 20 traffic to the main track only.

2. An automatic switching system for railway tracks comprising a main track and a side track, a switch connecting said tracks, a power operated switch movement for operating said switch, a 25 block system on said tracks establishing a normal space interval when running of at least one block between trains, a block relay for each block, automatic means controlled by a pair of said block relays for operating said switch movement and 30 means for preventing the operation of said switch movement by the trains as long as the space interval between the trains is more than a block in length.

3. An automatic switching system for railway 35 tracks comprising a main track and a side track divided into blocks, a block system controlling traffic on said tracks, a switch connecting said tracks, automatic means for operating said switch, means including said block system in a 40 pair of adjacent blocks for bringing said automatic means into operation when said blocks are occupied, said blocks being so arranged that under normal conditions they are not both occupied by trains at the same time.

4. An automatic switching system for railway 45 tracks comprising a main track and a side track, divided into blocks, a block system controlling traffic on said tracks, trains on said track spaced by said block system, a switch connecting said 50 tracks and means including said block system whereby trains in a pair of adjacent blocks on said side track, at the same time, operates said switch to the normal position, and means whereby trains on a pair of adjoining blocks on said 55 main track, at the same time, sets up conditions for operating said switch to the reverse position, the block closest to the switch being longer than the other block.

5. An automatic switching system for railway 60 tracks comprising a main track and a side track divided into blocks and having a translating device in each block responsive to the presence of a train in the block, a switch connecting said tracks, a stick relay controlling said switch, and said 65 translating devices on certain adjacent blocks when responding to trains at the same time, establishing the circuit of said stick relay.

6. In a railway system, the combination of a 70 track, a second track with a connecting switch, means for operating said switch to direct traffic from one track to the other and means co-operatively operated by cars spaced from each other, after passing the switch, a predetermined dis-

tance, for initiating the operation of said switch operating means.

7. In a railway system, the combination of a track, a second track with a connecting switch to the first track, a stick relay controlling the operation of said switch, means operated by cars spaced a predetermined distance on one of said tracks for energizing said stick relay and means for holding said relay energized by the position of said switch until the switch has been operated. 10

8. In a railway system, the combination, a main track, a second track, a switch connecting said tracks, a mechanism for operating said switch, a block system dividing said track into blocks to provide a predetermined spacing of 15 trains on the tracks, and having a block relay for each block, a stick relay having a pick up circuit and a holding circuit and when energized operating said mechanism to move said switch, and means for establishing the pick-up circuit of said 20 stick relay when the spacing of trains is below normal to deenergize the block relays in adjacent blocks at the same time.

9. In a railway system, the combination, a main track, a second track, a switch connecting 25 said tracks, a mechanism for operating said switch, a block system dividing said tracks into blocks and having a block relay for each block, a stick relay having a pick up circuit and a holding circuit and when energized operating said mechanism to move said switch to one position, means for establishing the pick up circuit of said stick relay by a pair of said block relays, means for interrupting said holding circuit by the movement of said switch and a circuit controlled by 30 said stick relay in the deenergized position for operating said switch to another position.

10. A railway system as in claim 9 in which the pick up circuit of the stick relay is controlled by the block relays for the blocks of the 40 conjoining tracks.

11. In a railway system, the combination, a track, a second track, a switch connecting said tracks, a mechanism for operating said switch, a block system dividing said tracks into blocks and 45 having a block relay for each block, a relay for operating said mechanism to cause a movement of said switch, means for establishing the circuit of said relay by the block relays in a pair of adjacent blocks in the deenergized position, the 50 block closest to the switch being longer than the adjacent block so that a train running at normal speed will pass over the shorter block in less time than it passes over the longer block.

12. In a railway system, the combination, a 55 main track, a side track of limited length connecting by a switch at both ends to said main track, a mechanism for operating the switch at the entering end of the side track, a block system controlling train movements on both of said 60 tracks, means whereby trains may enter and leave said side track at the same time, means controlled by said block system on the side track for automatically operating the entering switch to divert traffic from the side track to the main 65 track when traffic accumulates on the side track owing to the movement of traffic from the side track being less than the movement of traffic to the side track and means including said block system controlling the leaving switch to permit the accumulated traffic on the side track to move 70 without interruption from the side track to the main track.
